mann, doing business as Lippmann Engineer-
ing Works

Application June 13, 1938, Serial No. 213,382

1 Claim. (Cl. 209—44)

This invention relates generally to improvements in the art of treating granular material, and relates more particularly to improvements in the construction and operation of mechanism for washing, dehydrating and classifying materials such as sand or the like.

A general object of our invention is to provide an improved sand classifier which is adapted to thoroughly cleanse the granules and to separate the same into accurate grades.

In the construction of concrete structures, it has been found essential in order to produce structures having maximum strength and durability, to utilize ingredients of the highest quality. While considerable attention has heretofore been given to the production of high quality cement, and efforts have been made to thoroughly wash sand which was to be used in concrete work, not a great deal of attention has been paid to the matter of grading the sand ingredient used in concrete work of different types. We have discovered that while the removal of foreign substances such as silt is important, it is also important that the sand particles be accurately graded as to size for various classes of concrete construction. For example, very fine graded sand has been found desirable as an ingredient in one type of concrete mixture, while medium size graded sand is more desirable in another type of mixture, and coarse graded sand is still more desirable in other types of concrete.

It is therefore a more specific object of our present invention, to provide an improved mode of accurately and commercially classifying mixed sand particles, while at the same time thoroughly cleansing the sand.

Another specific object of the invention is to provide a new and useful sand classifier having enormous capacity and operable with minimum power consumption to effectively separate sand particles into accurately segregated grades.

A further specific object of the present invention is to provide an extremely simple and durable sand washing, grading and dehydrating machine which is highly efficient in use.

These and other objects and advantages of the present invention will be apparent from the following detailed description, and some of the novel features of separator construction which are illustrated and described but not specifically claimed herein, form the subject of our copending application Serial No. 196,859, filed March 19, 1938.

A clear conception of several embodiments of our present invention, and of the mode of con-

structing and of operating sand washing, dehydrating and grading machines built in accordance with the improvement, may be had by referring to the drawings accompanying and forming a part of this specification wherein like reference characters designate the same or similar parts in the various views.

Fig. 1 is a somewhat diagrammatic central longitudinal vertical section through a multiple deck sand washer, classifier and dehydrator; 10

Fig. 2 is a transverse vertical section through the machine of Fig. 1, taken along the line 2—2;

Fig. 3 is a more diagrammatic longitudinal section through a modified type of the improved apparatus; 15

Fig. 4 is a similarly diagrammatic longitudinal section through another modified type of our apparatus;

Fig. 5 is a top view of another commercial embodiment of our invention; 20

Fig. 6 is a central longitudinal vertical section through the machine of Fig. 5;

Fig. 7 is a transverse vertical section through the apparatus of Figs. 5 and 6, the section having been taken along the line 7—7 of Fig. 6; and 25

Fig. 8 is an end view of the machine of Figs. 5, 6 and 7, looking toward the sand discharge end.

While our invention has been shown and described herein as being especially applicable to machines for washing, classifying and dehydrating mixed sand, it is not intended to thereby unnecessarily restrict the scope. 30

Referring to the drawings and particularly to Figs. 1 and 2, the improved washing, classifying and dehydrating machine shown therein, comprises in general a main support or frame 9 supported or suspended in any suitable manner; an auxiliary frame 10 suspended from the main frame 9 by means of four parallel inclined links 11 and by coil springs 12 coacting with inclined guide rods 13; actuating mechanism interposed between the corresponding ends of the frames 9, 10 and adapted to vibrate the auxiliary frame 10 relative to the main frame 9; a receptacle 14 attached to and movable with the frame 10 and having a liquid or water basin 15 in the lower portion thereof; several superimposed upper screen decks 16, 17 disposed within the upper portion of the vibratory receptacle 14; and a plurality of superimposed lower inclined screens 18, 19, 20 confined within the lower portions of the receptacle 14 and extending into the liquid basin 15. 45

The lower frame 9 may be either rigidly or resiliently supported or suspended in any suitable 50

manner, and the auxiliary frame 10 is U-shaped and coacts only with the opposite sides and with the driving end of the receptacle 14. The links 11 are swingably attached to both of the frames 9, 10 by means of pins 21, and these links extend upwardly and forwardly relative to the receptacle. The inclined guide rods 13 have their upper ends rigidly attached to the auxiliary frame 10, and extend upwardly and rearwardly substantially perpendicular to the links 11. The cushioning springs 12 embrace the lower ends of the rods 13, and coact at their lower ends with sockets 22 secured to the main frame 9, and at their upper ends with collars 23 secured to the rods 13. These coil springs 12 are not essential and may be omitted or replaced by any other type of resilient means.

The actuating mechanism for vibrating the auxiliary frame 10 relative to the main frame 9, comprises a horizontal drive shaft 24 rotatable in bearings 25 carried by the main frame 9 and having an eccentric portion 26; a belt drive 27 for imparting rotation to the shaft 24; one or more vertical rods 28 rigidly attached to the auxiliary frame 10 and depending therefrom; and one or more blocks 29 slidable along the rods 28 and coacting with the eccentric portion 26. The driving assemblage is preferably such that rapid rotation of the shaft 24 will impart rapid vibratory movement to the receptacle 14, and the amplitude of vibration is preferably quite small.

The receptacle 14 is entirely open at its rear end, and has a gradually inclined bottom 30 which may be lined with screening or other material providing a roughened surface, and the inclination of the bottom 30 causes the liquid basin 15 to gradually increase in depth proceeding toward the front of the machine. The uppermost screen deck 16 is approximately horizontal and has relatively large screening perforations, and this screen deck is adapted to receive the raw mixed material from a supply chute 31, and is also subjected to liquid spray jets directly from nozzles 32. The other upper screen deck 17 is disposed parallel to the top screen deck 16 but has smaller screening openings therein, and both of the upper decks 16, 17 terminate at the rear open end of the receptacle 14. The lower inclined screens 18, 19, 20 are disposed substantially parallel to the inclined bottom 30 of the receptacle 14, and the upper inclined screen 18 has coarser mesh than the intermediate screen 19, while the screen 19 has coarser mesh than the lowermost screen 20. As previously indicated, the forward ends of the screens 18, 19, 20 are immersed in the liquid of the basin 15, and the rear discharge ends thereof terminate at the open end of the receptacle 14. It is to be noted that the delivery ends of all of the screens 16, 17, 18, 19, 20 are staggered or out of vertical alignment, so that independent material conveying chutes may be associated with the several screen ends to convey the several grades away from the machine; and in this machine, excess liquid from the basin 15 together with silt and other foreign matter, are discharged directly from the upper end of the inclined bottom 30.

During normal use of the sand washing, grading and dehydrating machine of Figs. 1 and 2, the driving shaft 24 is being constantly rotated to cause the eccentric portion 26 to move the blocks 29 in a manner to rapidly vibrate the receptacle 14 and its contents upon the suspension links 11 and springs 12. While the receptacle 14 is thus vibrating, it is being guided to move

in a definite path by the links 11, and the springs 12 function to cushion the downward motion and to assist the links and driving mechanism in moving the receptacle upwardly. Liquid such as water is being constantly delivered in regulated quantities from the nozzles 32 to the uppermost screen deck 16, and the mixed sand is being dumped from the chute 31 upon this deck and is being directly subjected to the washing action of the admitted liquid. The particles of the admitted material which are too large to pass through the screen deck 16, are urged therealong by the vibration, and are promptly delivered from the machine; and the remainder of the material is deposited upon the screen deck 17, where the second grade of oversize particles is separated and removed. The mixed finer particles are delivered from the lower deck 17 together with the liquid, directly into the vibrating basin 15 where the heavier sand and silt particles descend toward the upper inclined grading screen 18. Due to the vibration of the basin 15 and of the screens 18, 19, 20 disposed therein, the descending sand particles as well as the screens, are subjected to thorough washing and flushing action. The coarse grade sand particles which are deposited upon the upper screen 18 within the basin 15, are conveyed upwardly therealong by the vibratory movement and are ultimately removed from the basin and discharged from the rear open end of the machine, while the finer sand particles and silt are subjected successively to the washing and grading action of the lower inclined screens 19, 20 so as to separate two additional grades of clean sand. The silt and other heavier foreign matter which is removed from the sand, is eventually deposited upon the roughened bottom 30 and is conveyed upwardly along this bottom by the vibration, being finally discharged from the rear open end of the receptacle 14 together with the excess liquid and the floating dirt or foreign substances. In this manner, the mixed sand particles are thoroughly washed, accurately graded, thoroughly dehydrated, and finally delivered from the constantly vibrating receptacle 14.

In Fig. 3, we have shown diagrammatically, a machine of simplified construction wherein the upper coarse screen decks have been omitted entirely, and in which the lower grading screens 18, 19, 20 have also been obviated. In this machine, the receptacle 14' is of modified construction, but the suspension and driving mechanisms may be the same as in Figs. 1 and 2. The receptacle 14' has a modified bottom 30', the inclined rear portion of which is preferably roughened and extends from beneath the basin 15 to a point considerably above this basin at the extreme rear end of the machine. The side of the receptacle 14' is provided with a liquid overflow 31 for the basin 15, and such an overflow may be provided at each side of the basin. When this modified machine is operating normally, the mixture of sand and water is deposited into the basin 15 near the front end of the receptacle 14', and due to the constant vibration of the receptacle and of the liquid in the basin, the sand is thoroughly washed while travelling through this turbulent liquid and over the horizontal portion of the bottom 30'. When the solids reach the roughened inclined portion of the bottom 30', they are gradually elevated and removed from the liquid, being eventually discharged from the rear open end of the receptacle 14'. The excess liquid together with the floating foreign sub-

stances, are constantly discharged through the overflow 31, and with this modified structure no independent grades of sand are produced.

In Fig. 4 we have illustrated another slightly modified type of machine similar to that of Fig. 3 but having a single coarse or scalping screen deck 32 therein. The operation of this second modified separating machine is quite similar to that of Fig. 3, but the screen deck 32 functions to initially remove oversize particles from the admitted material.

Referring to the commercial machine shown in Figs. 5 to 8 inclusive, this device again embodies the principle of washing and grading within a vibrating liquid basin, after the coarser materials have been removed from the raw material. This further modified and improved sand classifier comprises in general a main support or frame 39 which may be mounted or suspended in any suitable manner; an upper coarse screen support 40 movably suspended from the main frame 39 by means of levers 41 which are swingably suspended from cross rods 42 which are supported in bearings 43 carried by the frame 39; a receptacle 44 swingably suspended from the lower ends of the levers 41 and having a liquid basin 45 therein; upper and lower coarse screen decks 46, 47 carried by the support 40 above the basin 45; and lower inclined fine screens 48, 49, 50 removably confined within the receptacle 44 and extending into the liquid basin 45.

The main frame 39 is of rigid U-shaped formation, and is open at the center so that the receptacle 44 may be vibrated without obstruction, and the screen support 40 is located entirely above the main frame 39 and is vibratable simultaneously with but oppositely of the receptacle 44. Stationary apron plates 51 may be suspended from the rods 42 at the opposite sides of the support 40 and receptacle 44 so as to insure proper delivery of material from the former to the latter. The bottom 52 of the receptacle 44 is inclined upwardly and rearwardly, and the lowermost portion of the basin 45 is preferably provided with a drain pipe 53. The rear end of the receptacle 44 is open, and the lower fine screens 48, 49, 50 are superimposed and are of successively diminishing length in order to facilitate delivery of the several grades of sand to independent final delivery chutes.

The actuating mechanism for vibrating the screen support 40 and the receptacle 44, comprises a horizontal drive shaft 54 rotatable in adjustable bearings 55 carried by the main frame 39 and having an eccentric portion 56; a driving pulley 57 for imparting rotation to the shaft 54; and a connecting rod 58 coacting with the eccentric shaft portion 56 and with a pivot pin 59 carried by the front end of the support 40 and by the upper ends of the front levers 41. The driving arrangement is such that when the shaft 54 is rotated rapidly the eccentric portion 56 acting through the connecting rod 58 will impart rapid vibration to the screen support 40 and will simultaneously impart similar but opposite vibration to the receptacle 44 through the levers 41.

During normal operation of the further improved commercial washing, grading and dehydrating machine of Figs. 5 to 8 inclusive, the upper support 40 and the receptacle 44 are being constantly vibrated by the revolving shaft, and liquid is being delivered to the upper screen deck 46 from the nozzles 32. The mixed material may then be delivered onto the forward end of the

upper deck 46 and is subjected to the washing action of the jets. The oversize particles are separated from the finer material by the screen deck 46 and are delivered from the machine at the rear end of this deck, while the finer material and liquid pass through the upper deck and are deposited upon the coarse screening deck 47. This deck 47 separates the second grade of oversize particles, and deposits the fine particles and liquid into the vibrating liquid basin 45. In the basin 45 the heavier sand particles descend upon the upper inclined screen 48 where the coarser sand grade is removed from the finer particles and is elevated out of the basin by the vibrating screen 48, being finally discharged from the upper rear end thereof. The material which passes through the screen 48 is deposited upon the intermediate inclined screen 49 which separates the second grade of sand and removes the same from the basin 45 and delivers it from the rear end of the machine. The fine particles which pass through the screen 49 are deposited upon the lower screen 50 where the fine sand grade is separated from the silt, and is removed from the basin 45 and discharged from the rear end of the receptacle 44. The silt and other very fine solid particles which pass through the lower screen 50, are deposited upon the vibrating roughened inclined bottom 52 and are ultimately delivered from the rear end of the receptacle 44 together with the excess liquid and floating foreign material. In this manner, the several grades of solids are quickly and accurately separated, thoroughly washed, dehydrated, and delivered from the machine. The opposite vibration of the upper support 40 and receptacle 44, tends to eliminate undesirable vibration of the main frame 39, and the screens 48, 49, 50 of this machine are readily removable to permit cleaning and drainage of the basin 45.

From the foregoing detailed description it will be apparent that our invention provides a simple and compact sand classifier which is adapted to rapidly and effectively wash, grade and dehydrate the sand particles. The provision of a vibrating liquid basin within which the washing and grading is effected, is an important feature of our present invention, and the dehydration is automatically effected by the inclination of the separating screens which elevate the separated grades out of the liquid basin and thereafter permit drainage of liquid prior to final delivery of the product from the machine. The disposition of the fine grading screens beneath the surface of the liquid within the vibrating basin, not only insures more accurate grading, but also prevents clogging of the screens, and these screens may be made readily removable for cleaning purposes. It is also preferable to construct these separating machines so that the grading screens will be vibrated in the general direction of their inclination in order to enhance the conveying action, it is also desirable to roughen the bottom of the receptacle in any suitable manner in order to insure most effective discharge of the silt and other foreign matter. Our improved classifying machine has proven highly successful in actual use, and produces separated grades of sand which are accurate as to size and which are thoroughly cleansed and therefore especially adapted for use in concrete work.

It should be understood that it is not desired to limit our invention to the exact details of construction or to the precise mode of operation, herein shown and described, for various modi-

fications within the scope of the claim may occur to persons skilled in the art.

We claim:

5 In combination, a receptacle having an inclined bottom and a liquid basin of considerable depth above said bottom, a series of superimposed parallel screens disposed parallel to said bottom and each having a substantial portion thereof con-

stantly immersed in said basin, means for delivering granular material to the deepest portion of said basin above the upper of said screens, and means for vibrating said receptacle and screens in the general direction of the inclination of said bottom. 5
